DESIGN FOR A HOLDER FOR FLUORESCENT LAMPS AND STARTER SWITCH

Darwin Curtis, Winnetka, Ill.

Application April 8, 1942, Serial No. 106,494

Term of patent 7 years

To all whom it may concern:

Be it known that I, Darwin Curtis, a citizen of the United States and resident of Winnetka, in the county of Cook and State of Illinois, have invented a new, original, and ornamental Design for a Holder for Fluorescent Lamps and Starter Switch, of which the following is a specification, reference being had to the accompanying drawing which forms a part thereof.

Figure 1 is a perspective view of a holder for

fluorescent lamps and starter switch showing my new design.

Figure 2 is a perspective view thereof showing the side opposite to that illustrated in Figure 1.

I claim:

The ornamental design for a holder for fluorescent lamps and starter switch substantially as shown.

DARWIN CURTIS.
